ABRADING TOOL

Theodore M. Schupp, Richfield Township,
Summit County, Ohio

Application March 22, 1938, Serial No. 197,405

8 Claims. (Cl. 15—212)

This invention is an improved abrading tool for cleaning or scouring the interior cylindrical surfaces of a certain class of pipe fittings.

In modern high grade plumbing and heating systems, and other pipe installations such as those used in air conditioning systems, brass and copper pipes and fittings are employed, and the joints between the pipes and fittings are of the threadless type, the joined surfaces being connected together by soldering or so-called sweating or brazing.

When fittings of this class are kept in stock for an appreciable length of time, and when they are carried about and handled, corrosion occurs on the surfaces of the fittings and also said surfaces are subjected to the accumulation of dirt and grease. Before an effective and satisfactory joint can be made, the surfaces that are to be connected together in the aforesaid manner have to be cleaned or cleared of all foreign substances preparatory to receiving the flux and solder.

An object of my invention is to provide a simple, inexpensive, and durable tool by which the interior surfaces or joint seats of tubular fittings may be effectively and conveniently cleaned.

Another object of the invention is to provide an abrading tool in which a quantity of steel wool or similar material forms the abrading part or element; and a related object is to provide a construction facilitating the insertion, replacement and adjustment of the abrading material.

The tool, according to the present embodiment of the invention, comprises a tubular body that is open at its forward end and along one side adjacent said end to provide an open side cavity in which the abrading material is packed and through whose open side the material is exposed for action on the surface or seat to be cleaned. A further object is to provide a movable closure for the open side of the tubular body, desirably in the form of a sleeve that is frictionally engaged with and slidable on said tubular body, and by which the abrading material may be confined while being packed or compressed in the tool, and which closure or sleeve may serve as a retainer and protector for the abrading material when the tool is not in use.

Another object is to provide a part on the tool for cooperation in the manner of a stop with a part of the fitting thereby to dispose the abrading element in proper relation to the interior seat of the fitting when the end of the tool is inserted into the fitting.

Objects and advantages additional to the foregoing will appear as I proceed to describe the

invention by reference to the accompanying drawing wherein Fig. 1 is a perspective view illustrating the manner in which the tool is used for cleaning or scouring the internal cylindrical seat of a pipe fitting, the latter being shown in central section; Fig. 2 is a perspective view of the tool; Fig. 3 is a central longitudinal section through the tool and through an adjacent portion of a fitting into which the end of the tool is inserted, the tool being shown in contracted condition; Figs. 4, 5 and 6 are sections on the respective lines 4—4, 5—5 and 6—6 of Fig. 3, the several views being taken as though looking in the direction of the arrows associated with said lines, and Fig. 7 is a sectional detail through the rear end of a modification of the invention.

The tool includes a body 1 that is constructed of a piece of tubing of suitable length. Within the tubular body is disposed a cylindrical block 2 provided with a longitudinal groove 3 along one side. The front end of the block 2 is spaced from the corresponding end of the body a distance somewhat greater than the depth of the deepest seat that is to be cleaned by means of the tool, and one side of the tubular body portion forwardly of the block 2 is cut away so as to provide a side opening. Said opening occupies less than half the circumference of the body and the longitudinal edges of the remaining segmental part of the body are turned inward slightly, as shown at 4 in Figs. 2 and 4. The block 2 is arranged with its groove 3 diametrically opposite the aforementioned side opening.

A unit, designated generally by the reference numeral 10, and including a substantially semi-cylindrical presser jaw 11 and a similarly shaped handle 12, is pivotally connected, by means of a pin or rivet 15, to the body 1. Said pin or rivet is engaged through apertures in ears 16 of the unit 10, and extends through aligned openings in the body 1 and block 2. The presser jaw 11 and the handle 12 are disposed at an obtuse angle to each other, and a leaf spring 17, that is shown as connected by a rivet 18 to the free end of the handle 12, is located between the handle 12 and the rear end portion of the body 1 and tends to urge the handle outwardly thereby to swing the presser jaw 11 inwardly against the front end of the body. The jaw 11 terminates in the transverse plane of the front end of the body 10 and, as is especially clear from Fig. 2, the unit 10 is spaced a slight distance from the body 1. Surrounding the body forwardly of the pin or rivet 15 is a sleeve 20, the same preferably being split longitudinally and constructed of resilient

metal so as to frictionally embrace the body. This sleeve constitutes a closure for the previously mentioned side opening.

Extending through the body from end to end thereof is a rod 22 that is slidable within the groove 3 of the block 2 and its forward end is turned laterally to provide a finger 23, the same being shown as at an angle slightly acute to the longitudinal axis of the rod. At its rear end the rod extends through a bore 25 in a plug 26 that is set within the end of the body 1 and is held in place by a screw 27. Beyond the plug 26 the terminal portion of the rod 22 is bent laterally and formed to provide an eye 28. A coil spring 30 surrounds the rod 22 rearwardly of the block 2, the bore 25 of the plug 26 being large enough to permit free movement of the rod and spring therethrough. As will best appear from Fig. 5, the groove 3 is of a width only slightly greater than the diameter of the rod 22, and as a consequence the front end of the spring 30 bears against the surface of the block adjacent the groove 3, while the rear end of the spring bears against an abutment provided by the laterally turned end of the rod.

A slight modification of the foregoing construction is shown in Fig. 7 where a fragment of the tubular body is designated 1^a, and fitting into the rear end thereof is a plug 26^a which may have precisely the same cross-sectional area and shape as the block 2. In fact, the block and plug may be cut from the same bar of stock, having a groove along one side, corresponding to the before-mentioned groove 3, the groove of the plug 26^a being designated 25^a and serving to accommodate the rear end portion of the rod 22^a. In this case the rear end of a spring 30^a engages an abutment provided by a ring or washer 31 that surrounds the rod 22^a and is held against rearward movement thereon by lugs 32 that may be produced by pinching the rod at these points to displace the metal thereof.

A pipe fitting designated 35 appears in Figs. 1, 3 and 4. It is shown as a T-fitting, the lateral branch 36 whereof is of smaller diameter than the main branch. Within each terminal of the fitting is a cylindrical seat that is adapted to receive the end of a pipe to which the fitting is to be sweated or brazed, and preparatory to executing the joint the surface of the seat is cleaned or polished by means of the tool. The tool herein disclosed is of a size to clean the larger seats of the main branch of the fitting. A tool of a smaller size would be employed for cleaning the seat of the branch 36.

In preparing the tool for use, the closure or sleeve 20 is shifted forwardly along the body 1 until its front end is substantially flush with the corresponding ends of the body and jaw 11. The rod 22 is grasped by the eye 28 and pushed forwardly and turned through approximately 180° so as to engage the finger 23 with the front end of the body portion and with the adjacent end of the jaw 11. This holds the rod in a forwardly projected position against the action of the spring 30. The user now places a quantity of steel wool or similar abrading material, designated 38, in the open end of the tool and presses or tamps it to the desired density, using a sufficient quantity to thoroughly fill the tool to the very end, and he then turns the rod 22 by means of the eye 28 to engage the finger 23 across the front end of the body of abrading material and then releases the rod to permit the spring 30 to retract it and, through the means of the finger

23, hold the abrasive material firmly against the front end of the block 2. The user then slides the sleeve 20 rearwardly beyond the side opening of the body portion and, grasping the tool in the manner shown in Fig. 1, inserts the front end of the tool into the end of the fitting until the end of the jaw 11 engages a shoulder 39 at the inner end of the cylindrical seat 40 that it is desired to clean. Now, by squeezing the tool so as to force the handle 12 toward the adjacent end of the body 1, the front end of the tool is expanded. That is to say, the presser jaw 11 is brought into engagement with the adjacent side of the seat 40 and the exposed portion of the body of abrading material 38 is pressed into firm contact with the diametrically opposed portion of the seat 40 for a considerable distance thereabout. In the class of fittings referred to there is frequently a circumferential solder retaining groove 41 about the seat, and because of the nature of the abrading material a part of such material is forced into the groove. The user, continuing to squeeze the tool firmly with one hand, rotates or oscillates the fitting with respect to the tool by means of his other hand and thus cleans or scours the seat 40 throughout its circumference. When the tool is not in use, the sleeve 20 may be slid forwardly to the position shown in Fig. 2 thereby to protect and better confine the abrading material.

Having thus described my invention, what I claim is:

1. A tool of the class described comprising an elongated body having a side opening cavity adjacent its forward end, a quantity of abrading material in said cavity exposed through an open side thereof for action on a seat to be cleaned, and an elongated unit fulcrumed to the body and whose front and rear ends constitute, respectively, a jaw and a handle, the latter normally reposing in laterally spaced relation to the body and when swung toward the same serves to rock the unit thereby to cause the jaw to effect expansion of the forward end of the tool and a consequential outward movement of the abrading material.

2. A tool of the class described comprising a body, a presser jaw movably connected thereto and overlying one side of an end portion thereof, said end portion being hollow and having an opening on the side opposite said jaw, a quantity of abrasive material in the hollow end portion of the body and exposed through said opening for action on a surface to be cleaned, and means for forcing said jaw away from the body.

3. A tool of the class described comprising a body having an abrasive receiving cavity that opens through one end and through the side of the body adjacent said end, an abutment defining the inner end of the cavity, a wad of abrasive material in said cavity and exposed through the open side of the body for action on a surface to be cleaned, a presser jaw movably connected to the body and overlying the side of the end portion thereof opposite said open side, a spring urged element engaging and bearing inwardly against the outer end of the wad of abrasive material thereby to clamp it against the aforesaid abutment, and means for forcing the presser jaw away from the body.

4. A tool of the class described comprising a body, a presser jaw movably connected thereto and overlying one side of an end portion thereof, said end portion being hollow and having an opening on the side opposite said jaw, a closure

for said opening shiftable on the body to and from effective position, a quantity of abrasive material in the hollow end portion of the body and exposed through said opening for action on a surface to be cleaned when said closure is in ineffective position, and means for forcing the presser jaw away from the body.

5. A tool of the class described comprising an elongated tubular body, a block fitted within said body and having its forward end spaced inwardly a substantial distance from the corresponding end of the body, one side of the body being cut away from its forward end to a point adjacent the forward end of said block thereby to provide a side opening, a sleeve frictionally embracing the body for slidable movement thereon from a position in which its forward end is contiguous to the corresponding end of the body to a second position wherein its forward end is adjacent the rear end of said side opening, a unit pivotally connected to the body rearwardly of said sleeve when the latter is in its rear position and comprising a jaw that extends to the forward end of the body and a handle portion in angular relation to said jaw that extends to approximately the rear end of the body, spring means tending to rock said unit with respect to the body so as to retain the jaw adjacent the forward end of the body, and a quantity of abrasive material compacted within the forward end of the body and exposed through the side opening thereof for action on a surface to be cleaned.

6. A tool of the class described comprising an elongated tubular body, a block fitted within said body and having its forward end spaced inwardly a substantial distance from the corresponding end of the body to provide a cavity, one side of the body being cut away from its forward end to a point adjacent the forward end of said block thereby to provide a side opening for said cavity, a quantity of abrasive material in said cavity, a sleeve frictionally embracing the body for slidable movement thereon from a position in which its forward end is contiguous to the corresponding end of the body to a second position wherein its forward end is adjacent the rear end of said side opening, said block having a longitudinal passageway from end to end thereof, a member extending through the body and slidable in said passageway of the block, the member having a part for engagement with the abrasive material adjacent the open front end of the body and having an operating part extending beyond the opposite end of the body, a spring urging said member rearwardly, a unit pivotally connected to the body rearwardly of said sleeve when the

latter is in its rear position and comprising a jaw that extends to the forward end of the body and a handle portion in angular relation to said jaw that extends to approximately the rear end of the body, and spring means tending to rock said unit with respect to the body so as to retain the jaw adjacent the forward end of the body.

7. A tool of the class described comprising an elongated tubular body, one side of which is cut away adjacent the forward end of the body to provide a side opening, an abutment disposed within the body to the rear of said side opening, a quantity of abrasive material in the body exposed through said side opening for action on a seat to be cleaned, a member extending through the body and having a part for engagement with the abrasive material adjacent the open front end of the body and having an operating part extending beyond the opposite end of the body, a spring urging said member rearwardly thereby to clamp the abrasive material between the first mentioned part of said member and the aforesaid abutment, a unit pivotally connected to the body and comprising a jaw that extends to the forward end of the body and a handle portion in angular relation to said jaw that extends to approximately the rear end of the body, and spring means tending to rock said unit with respect to the body so as to retain the jaw adjacent the forward end of the body.

8. A tool of the class described comprising an elongated cylindrical tubular body, a cylindrical block fitted within said body and having its forward end spaced inwardly a material distance from the corresponding end of the body to form a cavity, the body being notched inwardly from its front end to a point adjacent the forward end of said block thereby to provide a side opening for said cavity, a quantity of abrading material in said cavity exposed through the open side thereof for action on a seat to be cleaned, a pivot pin extending through the body and through said block a material distance rearwardly from the front end of the block, a unit having side portions pivoted on the ends of said pin, the portions of said unit on opposite sides of its pivotal axis being disposed at an obtuse angle to each other, the forward end of said unit constituting a jaw that terminates in proximity to the front end of the body and the other end portion constituting a handle that extends alongside the rear end of the body, and a spring interposed between the body and unit and intending to rock the latter in a direction to retain the forward end of the unit in proximity to the corresponding end of the body.
